LUBRICATING DEVICE, PARTICULARLY
ADAPTED TO BE USED IN CONNECTION
WITH ROTARY DISTRIBUTORS FOR IN-
TERNAL COMBUSTION ENGINES

Jean Konstantinoff, Paris, France

Application October 24, 1931, Serial No. 570,866,
and in France October 27, 1930

2 Claims. (Cl. 123—190)

The present invention has for object a lubricating device more particularly adapted to be used in connection with the rotary distributors of the explosion or internal combustion engines and showing this particularity that the supply of oil to the movable members is secured therein simultaneously by splashing and under the action of pressure.

To this purpose, in the wall of the casing or jacket of the distributor are provided cavities constituting pockets connected, on the one hand, with a pump securing the circulation of the oil under pressure, and on the other hand, with the supply of oil used for lubricating by way of splashing the rolling members of the distributor, the said pockets being in communication with the interior of the jacket by means of channels or ducts supplying with oil the parts of the distributor which are in contact with the said jacket. It is accordingly possible to obtain a continuous admission of oil under pressure to the rubbing parts of the distributor, notwithstanding the fact that the splash lubrication replaces the lubrication under pressure in case the pump is stopped and that it is possible to obtain in this way a perfect and permanent lubrication of the distributor.

The putting into practice of the invention moreover comprises other important particularities which will be hereinafter described with reference to the accompanying drawings in which by way of example:

Figure 1 is an axial vertical section of a rotary distributor provided with a lubricator forming the object of the invention.

Figures 2, 3 and 4 show a form of construction of the casing or jacket of the distributor, shown respectively in a vertical, axial section, in elevation and in a horizontal section.

Figure 5 is a front view of the rubbing rings of the distributor.

Fig. 6 is a section made according to line 6—6 of Fig. 5.

Fig. 7 is a plan view from above of the case of four stroke cycle motor or engine, showing a particular arrangement of the lubricating circuit.

In the example as shown, the distributor comprises a rotary cylindrical body or liner 1, provided with inlet ports A and outlet ports E, and carrying packing rings 2, 3 of special construction. The said distributor revolves within the head 4 of the cylinder 5 in a cylindrical casing or jacket 6 provided, as well as the rings 2, 3, with ports corresponding to the orifices A and E.

This jacket 6 moreover comprises a fastening strap 6a by means of which it is secured to the

head 4 at same time as a cap 7 in which is mounted the spindle 1a of the distributor, ball bearings 8 and 9 being conveniently interposed to this purpose. The spindle 1a is provided with a driving gear 10 actuated by worm 11 and the whole is enclosed in a case 12.

The case 12 contains a supply of oil in which the ball bearing 8 is directly immersed and communicating through channels 13 drilled in the cap 7 with ball bearings 9. Ducts 14 allow the oil to arrive to the bearing of the spindle 1a. On the other hand, according to the invention, the external wall of the jacket 6 is provided with grooves 15 forming pockets in connection through ducts 16 with the ball bearings 9. The said grooves 15 are also in connection through ducts 17 with pipes 18 connected to the circulating circuit of an oil pump (not represented), supplied from the amount of splash oil contained in the case 12. Ducts 19, preferably of small diameter, lead the oil of the grooves 15 between the contact surfaces of the jacket 6 and of the rings 2 and 3. The latter are provided with recesses 20 allowing only annular contact surfaces 21 to remain along their edges and opposite which open ducts 19. Lubricating or oil grooves 22 the width of which corresponds substantially to that of the contact surfaces 21 distribute or deliver oil upon the latter.

In the case 12 can be disposed, as shown in the drawings (Figs. 1 and 7), pillars 23 supporting a cover 24 provided with a port 25 extending above the heads of the cylinders composing the engine. Around the port 25 is a flange 26 in which is provided a peripheric conduit 27 to which the supply pipe 28 of the oil pump is connected. To the said conduit 27 are furthermore branched pipes 18 supplying oil to the pockets 15 of every jacket 6. Above the worm driving mechanism of every one of the distributors are drilled in the flange 26 holes 29 allowing the oil to drop or flow, drop after drop, upon the organs of the said mechanism.

As it can be easily ascertained from the preceding description, the whole of these arrangements secure a perfect lubrication of the various parts of the lubricator.

On the one hand, the rolling organs are permanently immersed in the oil supply of the case 12. On the other hand, the surface of the distributor 1 receives a continuous supply of oil under pressure through the medium of the pockets 15 and the ducts 19 and precisely upon the rubbing or frictional parts of the said surfaces. The recesses 20 of the rings 2, 3 moreover allow the formation between the said parts of a curtain

oil which secures the regularity and the constancy of the lubrication. It can further be observed that, in case the pump would stop, the splash lubrication could replace the lubrication under pressure the pockets 15 being in communication with the supply of oil contained in the case through the medium of the ducts 15. Finally, as hereinbefore described, the lubrication of the worm 11 and of the pinion 10 is obtained by means of the flow of oil taking place through the ports 29.

Should the jacket 2 of the distributor be a movable one, the oil pockets might be constituted by holes made in the thickness of the wall of the said jacket.

I claim:

1. Lubricating device, particularly adapted to be used in connection with rotary distributors for internal combustion engines; comprising a distributor jacket provided with cavities forming pockets, means for supplying oil under pressure

to said pockets, a duct formed in said jacket for introducing oil from a different source to said pocket, and another duct for leading the oil collected in said pocket to the interior of the jacket.

2. In a lubricating device, a rotary cylinder, means cooperating with said cylinder for rotating the same, packing rings surrounding said cylinder, a jacket surrounding said packing rings, a rigid head surrounding said jacket, a cap, a fastening strap forming a part of said jacket and connected with said head and said cap, said jacket having longitudinal grooves forming oil containing pockets and also having a plurality of ducts, some of said ducts being adapted to lead the oil collected in one of said pockets into the interior of said jacket, others of said ducts cooperating with ducts formed in said cap for admitting oil into said pockets, and a pipe adapted to contain oil under pressure, said pipe projecting into one of said pockets.
